UNITED STATES PATENT OFFICE

114,685

DESIGN FOR A CRACKER TRAY

Pearl W. Mikesell, Dayton, Ohio

Application August 8, 1938, Serial No. 79,196

Term of patent 14 years

To all whom it may concern:

Be it known that I, Pearl W. Mikesell, a citizen of the United States, residing at Dayton, in the county of Montgomery and State of Ohio, have invented a new, original, and ornamental Design for a Cracker Tray, of which the following is a specification, reference being had to the accompanying drawing, forming a part thereof.

I claim:

The ornamental design for a cracker tray, substantially as shown.

PEARL W. MIKESELL.
